Cary E. Fall,
BY
E. T. Silvius,
ATTORNEY.

UNITED STATES PATENT OFFICE.

CARY E. FALL, OF WASHINGTON TOWNSHIP, BOONE COUNTY, INDIANA.

CHANGEABLE CLASSIFIED BUSINESS DIRECTORY.

Application filed January 19, 1922. Serial No. 530,392.

To all whom it may concern:

Be it known that I, CARY E. FALL, a citizen of the United States, residing in Washington Township, in the county of Boone and

5 State of Indiana, have invented a new and useful Changeable Classified Business Directory, of which the following is a specification, reference being had to the accompanying drawings, and to the letters and

10 figures of reference marked thereon.

This invention relates to a type of directory that is designed to be hung on a wall or elsewhere, and has reference more particularly to a directory by which different businesses may be advertised periodically.

15 An object of the invention is to provide a business directory of such construction as to be adapted to be placed on a wall or upon a table or to be rolled, or folded and carried for exhibition to prospective advertisers.

20 Another object is to provide a changeable classified business directory which shall be of such construction as to permit the use of stock or standard printed matter, particularly letter heads, which may be especially artistic and attractive, thus avoiding the cost of designing and printing advertising matter especially for a business directory.

25 A further object is to provide a sectional changeable business directory which shall be so constructed as to permit ready changes of classification and also additional classifications and advertisements, and which shall not be costly but yet be durable and economical in use.

30 With the above-mentioned and other objects in view, the invention consists in a hanger having advertisement holders and changeable business classifications of novel construction and arrangement permitting ready inspection of business advertisements; and, the invention consists also further in the parts and combinations and arrangements of parts as hereinafter particularly described and further defined in the appended claims.

35 Referring to the drawings,—Figure 1 is a front view of the improved business directory constructed substantially in accordance with the invention; Fig. 2 is an edge view of the directory in which advertisement holders thereof are differently arranged; Fig. 3 is a fragmentary vertical

section of the directory structure on an enlarged scale; and Fig. 4 is a fragmentary rear elevation of the structure.

Similar reference characters in the different figures of the drawings indicate corresponding elements or features of construction herein referred to in detail.

A practical embodiment of the invention comprises one or more hanger sections having each a plurality of advertisement holders composed principally of suitable fabric, which for outdoor use may be made water proof, and each holder preferably has a transparent front to constitute a pocket in which an advertisement may be removably placed and protected, the front of the holder preferably being water proof. Preferably two or more directory sections are arranged side by side and are connected to an upper back portion 1 that is common to all the sections and turned over to constitute a front panel 2 and inclosing a stiffening bar or rod 3, which may be composed of metal, to constitute a supporting head at the lower portion of which is a bending line 4 from which extends a holder flap 5. The front panel 2 has a suitable printed or painted heading 6 thereon, and the head of the directory may be secured to a wall or elsewhere by means of screws 7 with which the head is provided. A back panel 8 is arranged so as to extend downward from the directory head and its upper portion is secured to the back of the portion 1, it preferably having a broad portion 9 that extends up to the upper end of the portion 1 so as to receive the securing screws and afford firm support for the section. The fabric or cloth of which the back panel 8 is composed has a bending line 10 from which extends a holder flap 11, the latter being partially behind the flap 5. The remaining portion of each section is composed of similar back panels 12 secured at their upper edges to the lower portions of the next adjacent panels slightly above the bending lines 10, one having a holder 13 partially covered by the flap 11, and the adjacent panel below having a similar holder 14, partially covered by the flap 13. The holders may be variously stiffened so that when swung upward from the normal hinge portion the fabric will bend and permit the holder to have a hinge-like movement on the bending line 10. The panels of which the back of each section is composed may

be variously secured together, preferably by means of rows of stitching 15 arranged above each bending line 10.

It is designed that a slip of paper or card board containing a printed advertisement be suitably secured on the front of each holder, a standard size of letter head being conveniently and cheaply obtained by cutting it from a sheet of letter paper of 10 the establishment desiring to be advertised in hotels, railway stations or elsewhere. Preferably each holder has a celluloid front 16 arranged thereon and extending from the lower edge of the holder upward nearly to 15 the row of stitching 15, the front being secured in place by a bottom row of stitching 17 and side rows of stitching 18 and 19, to constitute a pocket having a transparent front. A suitable number of business 20 classification labels 20 are provided which are removably placed in the lower portions of the pockets, the labels having different classifying titles, as 21 and 22, to indicate the character of the different businesses, the 25 labels being arranged so that the classifications shall be in alphabetical order. Advertising slips or sheets 23 are placed in the pockets or otherwise secured to the fronts of the holders and extend behind the 30 labels 20, the different slips having different advertisements, as 24 and 25 thereon, the advertisements on the uppermost holders 5 being always visible, those on the remaining holders below being covered by overlapping upper holders, while all the labels are 35 always visible on the lower portion of the holders which extend down beyond the next adjacent upper holders.

In practical use the advertisements of 40 different lines of business are arranged on the holders and classified as may be desired with proper labels. Letter headings showing interesting public buildings or institutions, may be placed on the uppermost 45 holders instead of business advertisements. The directories may be hung on walls and others may be placed on desks in hotels, where they may be useful to travelers in readily finding locations of leading busi-

ness stores or factories, or professional men 50 whose place of business it may be desired to visit. The different holders may be readily swung up to reveal the advertisements beneath them. Any advertisement may be displayed through a particular 55 period of time and then be displaced by another advertisement, the classification label being changed accordingly if necessary. In case the directory is placed out doors the celluloid fronts protect the advertising from rain water, the overlapping holders readily shedding the water and preventing the water from entering the tops 60 of the pockets.

Having thus described the invention, what 65 is claimed as new is:

1. A changeable classified directory comprising a plurality of back panels and holder flaps integrally connected with the panels, the lower portions of the panels being arranged on and secured to the upper portions of adjacent panels, the upper portion of the uppermost one of the panels having a supporting head thereon, and a plurality of transparent sheets arranged on the fronts 75 of the holder flaps and secured thereto at the bottoms and the sides thereof.

2. A changeable classified directory comprising a head bar, a plurality of hanger sections connected to the head bar, each section comprising a hanger back and a plurality of advertisement holders connected at their tops to the back in spaced-apart relation, each holder having an open top pocket on its front and overlapping the upper portions of the lower adjacent pockets, the front of each pocket being transparent, and classification labels removably arranged in the bottoms of the pockets of the holders and below the bottoms of the upper adjacent 85 holders.

In testimony whereof, I affix my signature in presence of two witnesses.

CARY E. FALL.

Witnesses:

SCHUYLER C. LAURENCE,
WILLIAM H. SMITH.
